UNITED STATES PATENT OFFICE.

JOHN A. GARDNER AND JOHN O. CAUSEY, OF GRIFFON, NORTH CAROLINA.

TOBACCO-CURING BARN.

Application filed November 11, 1925. Serial No. 68,899.

This invention relates to a tobacco curing barn and aims to provide a novel construction of heating flues whereby an oil or gas burning furnace may be employed for supplying the heat to the barn, thereby reducing the size of the furnace to the minimum and consequently reducing the cost of constructing a curing barn.

Another important object of the invention is to provide means for utilizing the smoke and products of combustion for heating purposes prior to its passage from the barn.

A still further object of the invention is the provision of flues supported in such a way as to induce circulation of the products of combustion and prevent choking of the flues.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

30 Referring to the drawings:

Figure 1 is a plan view of a tobacco curing barn, the roof thereof being removed illustrating the flues.

Figure 2 is a sectional view taken on line 2-2 of Figure 1.

Figure 3 is a plan view illustrating the usual type of furnace equipped with heating flues constructed in accordance with the invention.

40 Figure 4 is a sectional view taken on line 4-4 of Figure 3.

Referring to the drawings in detail, the barn is indicated generally by the reference character 5 and which is of the usual and well known construction.

The reference character 6 indicates the furnace which in this particular form of the invention is of the oil burning type, and as shown, extends only a short distance within the barn proper.

Heat from the furnace 6 passes from the furnace at a point adjacent to its inner end and enters the flues 7 which are in communication with the inner end of the furnace by means of elbows 8. Flues 9 and 10 which are arranged on opposite sides

of the flues 7 are connected by the flues 11 and elbows 12, the flues 7 being also in communication with the flues 10, through the flues 13 and elbows 14.

60 Communicating with the flues 9 are the lateral flues 15 which communicate with the flues 9 through the flues 16, the flues 15 being also in communication with the outlet pipe 17, through the flues 18 and 19 respectively. The flues 18 and 19 extend along the front wall of the barn as clearly shown by Figure 1. The pipe 17 discharges the products of combustion into the smoke stack 20 which is positioned directly over the furnace 6 and exteriorly of the barn.

65 As shown by Figure 2 of the drawings, the flues 7 are inclined upwardly towards the rear wall of the barn, and the flues 9 are inclined above the flues 10 in a direction towards the rear end of the barn, while the flues 15 that communicate with the flues 9 are inclined towards the forward end of the barn thereby inducing a draft and insure against the products of combustion choking the flues.

70 Associated with the furnace is an oil feed tank 21 that communicates with the interior of the furnace, through pipes 22 and 23, the latter pipes being provided with suitable nozzles to direct oil to the interior of the furnace where it mingles with air under pressure supplied to the furnace by the tank 24 and pipe 25.

75 From the foregoing it will be seen that due to this construction, the products of combustion will be circulated through the various flues of the heating system of the barn to the end that no portion of the heat from the products of combustion will be wasted, and the barn will be thoroughly heated with the minimum amount of heat and fuel consumed.

80 As shown by Figures 3 and 4, the furnace which is indicated at 25' is of the usual solid fuel burning type and extends into the barn, its rear end terminating in proximity to the rear wall of the barn. Flues 26 and 27 communicate with the inner end of the furnace 25 and extend towards the front wall of the barn from where they pass laterally and communicate with the flues 27' which extend towards the rear end of the barn and laterally communicating with the flues 28 that extend forwardly and inwardly at 29, the inwardly extended por-

tions communicating with the chimney 30 through the pipe 31.

- In this form of the invention, the flues are also inclined with respect to each other 5 to cause the products of combustion to ascend. It might be further stated that this form of flue construction is especially adapted for the usual solid burning furnaces now in common use to the end that 10 a person may install the system of flues and connect them with the usual solid fuel burning furnace, eliminating the necessity of providing an oil burning furnace which incurs additional expense to persons having 15 curing barns provided with furnaces of the solid fuel burning type.

We claim:—

- In a tobacco curing barn, a furnace having its inner end extending into the barn, 20 flues connected with the furnace and communicating with the interior thereof, said

flues having their forward ends disposed adjacent to the front wall of the barn, said flues extending rearwardly to points adjacent to the rear wall of the barn, flues 25 communicating with the first mentioned flues and extending towards the front wall of the barn from where they extend rearwardly towards the rear wall of the barn, flues communicating with the last mentioned flues and arranged adjacent to the side walls of the barn, and flues extending in parallel relation with the front wall of the barn and communicating with the last mentioned flues for exhausting products of 30 combustion from the barn.

In testimony that we claim the foregoing as our own, we have hereto affixed our signatures.

JOHN A. GARDNER.
JOHN O. CAUSEY
